Waterbury, Conn., a corporation of Connecti-
cut

Application August 12, 1953, Serial No. 26,429

Term of patent 14 years

(Cl. D42—7)

To all whom it may concern:

Be it known that I, Frederick Lux, a citizen of the United States, residing at Middlebury, Connecticut, have invented a new, original, and ornamental Design for an Alarm Clock, of which the following is a specification, reference being had to the accompanying drawing, forming part thereof:

Fig. 1 is a front elevation of the alarm clock, showing my new design.

Fig. 2 is a side elevation of the same.

Fig. 3 is a top plan view of the same.

Fig. 4 is a rear elevation of the same.

Fig. 5 is a bottom plan view of the same.

The dominant features of the design reside in the portions shown in full lines.

I claim:

The ornamental design for an alarm clock, substantially as shown and described.
